UNITED STATES PATENT OFFICE.

ALBERT DAGER, OF EL PASO, TEXAS, ASSIGNOR OF ONE-HALF TO ROBERT H. CREWS,
OF EL PASO, TEXAS.

ROTARY ROLL-PAPER FEEDER FOR TWO-REVOLUTION CYLINDER PRESSES.

Application filed October 26, 1926. Serial No. 144,329.

The present invention relates to a rotary roll paper feeder for a two revolution cylinder press and the purpose of the machine is to provide a mechanical feeding attachment for ordinary hand feed cylinder presses, and by means of which any grade of paper from news print to the higher grades of book or bond stock in roll form is automatically cut and delivered to the feed guides of the press to which it is attached. This machine can be quickly removed from the press and when so removed, the press is restored to its former status and may be therefore fed by hand, with paper in sheet form and in the usual manner.

Another very important object of the invention lies in the provision of a device of this nature with an exceedingly simple construction, which is inexpensive to manufacture, durable, efficient and reliable in operation, not likely to easily become out of order, adjustable, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawings:—

Figure 1 is a side elevation of a machine embodying the features of my invention, Fig. 2 is a top plan view thereof,

Fig. 3 is a section therethrough substantially on the line 3—3 of Fig. 1,

Fig. 4 is a perspective view of a portion of the rack bar,

Fig. 5 is a detail view taken substantially on the line 5—5 of Fig. 3,

Fig. 6 is a detailed view of the structure for taking power from the shoo-fly-rod.

Referring to the drawings in detail, it will be seen that the numeral 5 denotes a platform from the sides of which rise standards 6 having journaled therebetween rolls 7 and 8. Ratchets 9 and 10 are loosely mounted on the shafts 11 and 12 respectively of the rolls 7 and 8 respectively. Dogs or pivoted pawls 13 and 14 are mounted respectively on rolls 7 and 8 and engage the ratchets 9 and 10 respectively. Gears 15 and 16 are fixed respectively to ratchets 9 and 10 to rotate therewith. A rack bar

17 is movable between the gears 15 and 16 and is meshed therewith. This rack bar 17 has a tongue and groove slidable connection 18 with a frame 19 supported on the platform 5. A rocker arm 20 is pivoted as at 21 on one end of the platform 5 and has a plurality of apertures 22. A link 23 has a pivotal connection 24 with one end of the rack bar 17 and is provided with a plurality of apertures 26. A bolt 27 is adapted to pierce one of the apertures 22 and one of the apertures 26 for pivotally engaging the link 23 with the rocker arm 20 and thus said pivotal engagement between the link and the arm may be varied to vary the length of the stroke of the rack bar. The numeral 28 denotes the shoo-fly-rod of the press and an arm or crank 29 is attached thereto and pivotally engaged with a connecting rod 30 which has laterally bent arms 31 extending to opposite sides thereof. One of the ends 31 is engaged with the crank 29 and the other end is engaged with the arm 20 by means of a bolt 32 piercing one of the apertures 22. As is well known the rod 28 rocks thereby oscillating the arm 29 for reciprocating the connecting rod 30 thereby oscillating the rock arm 20, and reciprocating the link 23 to impart rectilinear motion to the rack bar 17. As the rack bar moves in one direction it will impart rotary motion to the rolls 7 and 8 but when it moves in the other direction these rolls will remain stationary since the ratchet will not engage the pawls 9 but will merely slip past them. These rolls 7 and 8 only rotate in a direction to take paper from the roll of paper 33.

Uprights 34 are provided in their upper ends with slots 35 in which are mounted slides 36 pressed downwardly by springs 37 which may be tensioned as at 38. These slides 36 have mounted thereon a movable knife blade 39 associated with a fixed blade 40. Projections 41 are provided on the slides 36 and one of them has a roller 42 thereon. A ledge 43 extends longitudinally on one face of the rack bar 17 and has an inclined end 44 terminating in a parallel portion 45. An auxiliary ledge 46 has hinged thereto a ledge portion 47 which is normally held upwardly by spring means 48 so that this portion 47 forms a continuation of the ledge 43.

Referring particularly to Fig. 1, when the

rack bar 17 is moving to the left it does not impart any motion to the rolls 7 and 8 but as it moves to the right it imparts movement thereto. As the rack bar in its movement to the right reaches the end of its stroke, it will be seen that the roller 42 resting on the ledge 43 passes over the end thereof and drops off to the parallel portion 45. In so doing, this roller allows the springs 37 to expand and force the movable blade of the cutting mechanism downwardly for severing the paper. The paper will be delivered along the endless conveying mechanism illustrated diagrammatically at 50 in the well known manner and operable in any suitable manner from the printing press. Upon the left hand movement of the rack bar, the roller will travel up the incline 44 swinging the portion 47 upwardly and raising the knife against spring pressure.

A pressure bar 51 precedes the cutting blade in reaching the surface of the paper and holds same taut in order to keep it from shrinking or sagging. Thus, a sheet of paper is drawn from the roll 33, delivered to the feed guides of the press and cut with each forward motion of the rack 17. The length or width of paper according to the width of roll paper used, is determined on relative positions of rods 23 and 30 in respect to arm 20 as will be quite apparent.

An equalizing shaft 52 has an arm 53 extending under one projection 41 and an arm 54 extending over the other projection 35 so that the cutting bar is maintained in a horizontal position during its upward and downward motion, this shaft being journaled in suitable bearings 55 on the uprights 6.

It is thought that the construction, operation, and advantages of this invention will now be clearly understood without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A feeding mechanism of the class described including, in combination, a pair of rollers, pawl and ratchet mechanisms associated with the rollers, gears associated with the pawl and ratchet mechanisms, a rack bar mounted for rectilinear motion meshing with said gears, means for reciprocating the rack bar, and cutting means controlled by the motion of said rack bar.

2. A feeding mechanism of the class described including, in combination, a pair of rollers, pawl and ratchet mechanisms associated with the rollers, gears associated with the pawl and ratchet mechanisms, a rack bar mounted for rectilinear motion meshing with said gears, means for reciprocating the rack bar, and cutting means controlled by the motion of said rack bar, said cutting means comprising a cutting bar spring pressed downwardly and having an extension, a ledge on said rack bar under said extension to hold said blade upwardly, said ledge having an inclined down portion to allow the spring pressed cutter bar to move downwardly to sever the papers fed between the rolls.

3. A feeding mechanism of the class described including, in combination, a pair of rollers, pawl and ratchet mechanisms associated with the rollers, gears associated with the pawl and ratchet mechanisms, a rack bar mounted for rectilinear motion meshing with said gears, means for reciprocating the rack bar, and cutting means controlled by the motion of said rack bar, said cutting means comprising a cutting bar spring pressed downwardly and having an extension, a ledge on said rack bar under said extension to hold said blade upwardly, said ledge having an inclined down portion to allow the spring pressed cutter bar to move downwardly to sever the papers fed between the rolls, a link pivotally engaged with said rack bar, a rockable arm adjustably engaged with said link, and means for oscillating the arm.

4. A feeding mechanism of the class described including, in combination, a pair of rollers, pawl and ratchet mechanisms associated with the rollers, gears associated with the pawl and ratchet mechanisms, a rack bar mounted for rectilinear motion meshing with said gears, means for reciprocating the rack bar, and cutting means controlled by the motion of said rack bar, said cutting means comprising a cutting bar spring pressed downwardly and having an extension, a ledge on said rack bar under said extension to hold said blade upwardly, said ledge having an inclined down portion to allow the spring pressed cutter bar to move downwardly to sever the papers fed between the rolls, a link pivotally engaged with said rack bar, a rockable arm adjustably engaged with said link, a bar adjustably connected with said arm, and means for reciprocating the last-mentioned bar from the shoo-fly-rod of a press.

5. A device of the class described, including in combination, a supporting structure, a pair of rolls journaled in the supporting structure in superposed relation, a frame on the supporting structure having a groove therein, a rack bar having a longitudinally

- extending tongue slidable in the groove, gears meshing with said rack bar, pawl and ratchet mechanisms associated with said gears and said rolls so that the reciprocatory movement of the rack bar will impart intermittent motion to the rolls. 6. A device of the class described, including, in combination, a supporting structure, a pair of rolls journaled in the supporting structure in superposed relation, a frame on the supporting structure having a groove therein, a rack bar having a longitudinally extending tongue slidable in the groove, gears meshing with said rack bar, pawl and ratchet mechanisms associated with said gears and said rolls so that the reciprocatory movement of the rack bar will impart intermittent motion to the rolls, a pair of uprights included in the supporting structure and having slots, a cutter member having its ends projectable through the slots, springs in the slots pressing the cutter bar downwardly, an extension on the cutter bar, and means on the rack bar for holding said cutter bar upwardly throughout the major portion of its movement. 7. A device of the class described, including in combination, a supporting structure, a pair of rolls journaled in the supporting structure having a groove therein, a rack bar having a longitudinally extending tongue slidable in the groove, gears meshing with said rack bar, pawl and ratchet mechanisms associated with said gears and said rolls so that the reciprocatory movement of the rack bar will impart intermittent motion to the rolls, a pair of uprights included in the supporting structure and having slots, a cutter member having its ends projectable
- through the slots, springs in the slots pressing the cutter bar downwardly, an extension on the cutter bar, a ledge extending longitudinally of said rack bar and having an inclined end for holding said cutter bar raised except at the end of its stroke where the extension will engage the inclined portion so that the springs will push the cutter bar downwardly to cut. 8. A device of the class described, including in combination, a supporting structure, a pair of rolls journaled in the supporting structure having a groove therein, a rack bar having a longitudinally extending tongue slidable in the groove, gears meshing with said rack bar, pawl and ratchet mechanisms associated with said gears and said rolls so that the reciprocatory movement of the rack bar will impart intermittent motion to the rolls, a pair of uprights included in the supporting structure and having slots, a cutter member having its ends projectable through the slots, springs in the slots pressing the cutter bar downwardly, an extension on the cutter bar, a ledge extending longitudinally of said rack bar and having an inclined end for holding said cutter bar raised except at the end of its stroke where the extension will engage the inclined portion so that the springs will push the cutter bar downwardly to cut, an equalizer shaft journaled on the uprights and having an arm extending over the projection, a second projection on the cutter bar and an arm on the equalizing shaft extending under the second arm. 75

In testimony whereof I affix my signature.

ALBERT DAGER.
